DISPLAY STAND

Robert G. Brunner, 131 Clyde, Evanston, Ill.

Filed June 20, 1962, Ser. No. 70,617

Term of patent 14 years

(Cl. D80—9)

Fig. 2

I claim:

The ornamental design for a display stand, substantially as shown.
